TELEPHONE SYSTEM

Filed April 28, 1927

UNITED STATES PATENT OFFICE

THOMAS F. CROCKER, OF CHICAGO, ILLINOIS, ASSIGNOR TO RESERVE HOLDING COMPANY, OF KANSAS CITY, MISSOURI, A CORPORATION OF DELAWARE

TELEPHONE SYSTEM

Application filed April 23, 1927. Serial No. 187,223.

This invention relates to telephone systems in general, but is more particularly concerned with auxiliary equipment by which calls over one or a group of telephone lines may be answered and supervised from a common position.

In business offices and the like, it is often desirable to employ some scheme whereby calls to one or a number of telephones may be answered from one position, a stenographer's desk or an attendant's desk, for example, so that if the person called is not in his office at the time or is too busy to answer the call, the stenographer or attendant may answer the call. The object of this invention is the production of new and improved circuit arrangements for such a position whereby calls over one or a group of telephone lines may be answered and supervised.

20 The main feature of this invention is the extreme simplicity of the circuit arrangements, and these, with other features not specifically mentioned, and the operation thereof will be described in detail with the

25 aid of the accompanying drawing, which discloses the invention by means of the usual schematic circuit diagrams, and illustrates sufficient of an automatic telephone system in which it may be employed so that the invention may be easily understood and its utility appreciated.

Referring to the drawing, the apparatus between the two dotted vertical lines is located at the attendant's desk. The lines which the attendant is to supervise are accessible in the banks of connectors at the automatic switchboard and also terminate thereat in individual line switches. In the drawing, the line of substation A comprising conductors 2 and 3, which is accessible in the banks of the connectors such as connector C and which terminates in the lineswitch LS, is one of these lines. At the attendant's desk, for each one of these lines there is provided a key such as key K' by which the attendant may connect her telephone set O to any one of the lines, a key such as key K² for use in supervising a connection, two supervisory lamps such as lamp L' and L², and two relays for controlling the signalling and supervisory circuits.

A line for the attendant's private use may also be provided, and such is shown in the drawing comprising conductors 2' and 3'. This line is also provided with keys, lamps, and relays having substantially the same function as the keys, lamps, and relays of the other line shown, but differing in some details as will be described later.

Besides the attendant's telephone set, previously mentioned, there is also a buzzer B at this position for apprising the attendant of all incoming calls.

The substations of the telephone lines such as substation A shown are of the usual automatic type well known in the art. The attendant's telephone set may be of the same type as the substation A with the ringer removed.

The lineswitches LS and LS' may be of any suitable type, such as the well known rotary type; and the connectors C and C' may also be of any suitable type such as the well known Strowger vertical and rotary type. The other switches of the exchange are not shown, since they do not concern this invention.

With this general description of the apparatus in mind, a detailed description of the operation may now be given. For this purpose it will first be assumed that a call is extended to the line of substation A by way of the connector C. The connector C, after this line has been connected with, connects ground potential to the release conductor 4 and applies ringing current intermittently to the conductors 2 and 3 in the usual manner. Ringing relay 5 responds to this ringing current and in operating closes the circuit of relay 6 at contacts 7. Relay 6 operates and closes a circuit for the buzzer B at contacts 8, and closes a circuit for the lamp L² at contacts 10. At contacts 11, relay 6 short circuits the condenser 12, thereby placing a direct current bridge across the line conductors 2 and 3. This permits a flow of direct current through ringing relay 5 in series with the ring-cut-off relay (not shown) in the connector C during the silent period. Therefore relay 5 is held operated during the silent period, and as a result, relay 6 is maintained energized.

gized continuously during the intermittent application of ringing current to the line. The resistance of relay 5 plus the resistance R, however, is sufficiently high to limit the direct current flow through the ring-cut-off relay in the connector C to prevent its operation. The intermittent application of ringing current to the line conductors 2 and 3 also causes the bells at substation A to ring in the usual manner.

If the called party is in his office, which fact the attendant at the desk will in all probability know, she will disregard the lamp signal and the sounding of the buzzer for the time being. When the called party removes his receiver to answer the call, relay 5 will be short-circuited by reason of the bridge placed across the line conductors 2 and 3 at the substation A. Relay 5 thereupon releases its armature and opens the circuit of relay 6. Relay 6 then releases its armature and opens the circuit of the buzzer B at contacts 8 and opens the circuit of the lamp L² at contacts 10. Thus, the buzzer B is stopped sounding and the lamp L² is extinguished and the attendant is informed that the called party has answered. Further details of the connection are omitted since they do not concern this invention.

Should the called party not be in his office at the time this connection is extended, which fact the attendant will most probably know, she will operate the key K' and remove her receiver from her telephone set as soon as she is apprised of the incoming call, (or she may do this after the buzzer has sounded a reasonable length of time to assure her that the called party is not in his office at the time, or is too busy to answer). When the attendant removes her receiver and operates the key K', the attendant's telephone set is connected across the line conductors 2 and 3 by the closure of contacts 15 and 16 which has the same effect concerning the connection as though the called party had removed his receiver. Thus, relay 5 is again short circuited, which on releasing its armature causes relay 6 to release. The buzzer stops sounding and the lamp L² is extinguished as previously described. Operating the key K' also closes contacts 17 thereby closing a circuit for lamp L¹. The lighting of the lamp L¹ indicates to the attendant that her telephone set is associated with this particular line at this time.

The attendant may now converse with the calling subscriber and inform him of the absence of the person with whom he wishes to converse or give him such other information as the circumstances dictate. If the calling subscriber then replaces his receiver, the attendant may restore the key K' and replace her receiver thereby releasing the connection and restoring the apparatus to normal.

In order to describe a particular feature

of this invention, it will be assumed that the calling subscriber is particularly anxious to speak with the desired person if it be possible, in which case the attendant will inform the calling subscriber that she will attempt to locate the person with whom he wishes to converse, if he wishes to wait on the line. Assuming that this procedure is chosen, the attendant will operate the key K² and restore the key K¹ to disconnect her telephone set from this line, and then take such steps as necessary to locate the desired person, after which she may proceed to answer other calls. Throwing the key K² and restoring the key K¹ closes circuits for both lamps L¹ and L² which extend from ground on the release conductor 4 through contacts 18 closed by the operation of key K², the circuit for lamp L¹ also including contacts 9 and 19. The lighting of these two lamps now indicates to the attendant that the calling subscriber is waiting on this line.

If the desired person is located and he comes to the telephone, he may remove the receiver and commence conversation with the calling subscriber. When the conversation is finished, both subscribers will replace their receivers. This initiates the release of the connection and the automatic switches associated therewith in the usual manner, ground potential being removed from the release conductor 4. The removal of ground from the release conductor 4 opens the circuit of the lamp L¹ and L², thus causing these lamps to be extinguished. The extinguishing of these lamps indicates to the attendant that this connection has been released, whereupon she will restore the key K².

Should the calling subscriber become impatient while waiting for the desired person to be located and replace his receiver, again the connection would be released and ground removed from the conductor 4 causing extinguishment of the lamps L¹ and L². If another call were now extended to the line conductors 2 and 3 while the key K² were operated, relay 5 and relay 6 would again operate, the buzzer B would be sounded and the light L² would again be lighted, just as though the key K² were not operated. Lamp L¹ remains dark since its circuit is held open by the separation of contacts 9. The called party or the attendant, if the called party were not present, could again answer the call in the usual manner.

The attendant may make outgoing calls over her private line comprising conductors 2' and 3' and may also answer calls extended over this line in substantially the same way as in answering a call over one of the other lines. The lighting of the lamp L¹² when connection to this line is made indicates to her that the call is for her personally. She will therefore throw the key K¹¹ and remove her receiver as soon as the buzzer B sounds

and the lamp L^{12} lights and commence conversation. To make an outgoing call, the attendant removes her receiver and operates the key K'' , and then dials in the usual manner.

5 The key K^{12} has a particular function that the corresponding keys of the other lines do not have. Its lower springs are arranged to throw a direct bridge across the line conductors when the key K^{12} is operated. To describe the particular function of this key for this line it will be assumed that the attendant has made an outgoing call and is holding conversation with some subscriber 10 and that during this time a call comes in over one of the other lines which requires her attention. She may then operate the key K^{12} and hold this connection intact by virtue of the bridge across the conductors 2' and 3' 15 at contacts 20', and then by releasing the talking key K^{11} and operating the talking key for the line which requires attention, she may connect her telephone set with this other line. After she has given the other line the required attention she may again reconnect her 20 telephone set with her individual line by throwing the key K^{11} and releasing the corresponding key of the other trunk line, and then restore the key K^{12} . Thus the attendant 25 is able to temporarily disassociate her telephone set from one line and associate it with another, without releasing the first connection. As in the previous case, both lamps L^{11} and L^{12} light when the key K^{12} is operated, in this case indicating to the attendant 30 that she is holding up a connection on her private line. If the attendant is called over her private line, she may likewise momentarily interrupt her conversation and give 35 attention to another call. She may in this case also operate the key K^{12} while she is answering the other call, although of course the release of the connection is controlled by the calling party. The lighting of the two 40 lamps L^{11} and L^{12} , however keep her reminded that she has left a connection over her own line.

45 This completes the description of this invention. What is thought to be new and is desired to have protected by Letters Patent 50 is specifically pointed out in the appended claims.

What is claimed is:

1. In a telephone system, a line terminating in a lineswitch and accessible in the banks of connectors, said line comprising talking conductors and a release conductor, a ringing relay for said line controlled over the talking conductors, and a signal for said line controlled over the release conductor.

2. In a telephone system, an individual subscriber's line, an attendant's switchboard, means for extending a connection to said line and for automatically signalling the subscriber at the station, a signal thereon for op-

70 prising the attendant at the switchboard of the incoming call, a telephone set at said switchboard, means whereby the attendant may connect said telephone set to said line and answer the call in the event that the called subscriber does not answer the call, and a second signal operable after the attendant has answered the call, in case she does answer it, for apprising the attendant when the connection is released.

75 3. In a telephone system, individual subscribers' lines, and attendant's switchboard, means for extending a connection to any one of said lines and signalling the subscriber at the station thereon, a signal individual to each line for apprising the attendant the particular line being called, a telephone set, means whereby the attendant may temporarily associate said telephone set with any line called and answer the call in the event that the called subscriber does not answer the call, and a second signal operable after the attendant has answered the call, in case she has answered it, for apprising the attendant when the connection is released.

80 4. In a telephone system, a plurality of individual subscribers' telephone lines, each line having a station thereon, and means at one of the stations for apprising the subscriber thereat when ever a call has been extended to any one of said lines.

85 5. In a telephone system, a plurality of individual subscribers' telephone lines, each line having a station thereon, means at one of the stations for apprising the subscriber thereat whenever a call has been extended to any one of said lines, and means at said one of the stations for apprising the subscriber thereat to which line the call has been extended.

90 6. In a telephone system, a plurality of individual subscribers' telephone lines, each line having a station thereon, means at one of the stations for apprising the subscriber thereat whenever a call has been extended to any one of said lines, means at said one of the stations for apprising the subscriber thereat to which line the call has been extended, and means at said one of the stations for associating the telephone set of that station with the line to which the call has been extended.

105 7. In a telephone system, a plurality of individual subscribers' telephone lines, each line having a station thereon, means at one of the stations for apprising the subscriber thereat whenever a call has been extended to any one of said lines, means at said one of the stations for apprising the subscriber thereat to which line the call has been extended, means at said one of the stations for associating the telephone set of that station with the line to which the call has been extended, and means at said one of the stations for apprising the subscriber thereat when the call is terminated.

110 8. In a telephone system, a plurality of

subscribers' telephone lines, each line extending from an exchange to a subscriber's station, a telephone set at one of the stations, and keys whereby said telephone set may at any time be connected to any one of said telephone lines.

9. In a telephone system, a subscriber's line, a station thereon, a branch of said line, a second station on said branch, a signal at 10 said first station periodically responsive to the intermittent application of ringing potential to said line, a signal at said second station, and means at said second station responsive to the intermittent application of 15 ringing potential to said line for operating said second signal continuously.

10. In a telephone system, a subscriber's line, a station thereon, a branch of said line, a second station on said branch, a signal at 20 said first station periodically responsive to the intermittent application of ringing potential to said line to apprise the subscriber at said first station of an incoming call, a signal at said second station, and means at 25 said second station actuated responsive to the intermittent application of ringing potential to said line for continuously actuating said second signal to apprise the subscriber at said second station of the incoming call, 30 and deactuated responsive to the removal of the receiver at the first station to deactuate said second signal to apprise the subscriber at said second station that the call has been answered.

35 11. In a telephone system, a group of subscribers' stations, a line for each station connecting the station with an exchange, an attendant's line extending from said exchange to an attendant's station which is on the same 40 premises with said group of stations, a branch of each subscriber's line extending to the attendant's station, and a keyboard at the attendant's station comprising keys by means of which the attendant's telephone may be 45 disconnected from her line and may be connected instead to any one of said branches to answer a call.

12. In a telephone system in which the signal on a called line is operated by the 50 intermittent application of a source of alternating current potential to the called line and in which a source of direct current potential is applied to the line during the silent periods, a line, a first relay and a condenser 55 connected in series across the conductors of said line, said relay being responsive initially to current from said first source only, a second relay controlled by said first relay, and means controlled by said second relay for 60 short-circuiting said condenser, said relay being thereafter responsive to current from either source.

13. In a telephone system in which the signal on a called line is operated by the 65 intermittent application of a source of alter-

nating current potential to the called line and in which a source of direct current potential is applied to the line during the silent periods, a line, a first relay and a condenser connected in series across the conductors of said line, said relay being responsive initially to current from said first source only, a second relay controlled by said first relay, means controlled by said second relay for short-circuiting said condenser, said relay being thereafter responsive to current from either source, and a signal operated continuously under the control of said second relay during the intermittent application of alternating current to the called line.

14. In a telephone system, a line comprising talking conductors and a release conductor, a signal-control relay for the line controlled over the talking conductors, and a signal for the line controlled by said relay under certain conditions and controlled over the release conductor under certain other conditions.

15. In a telephone system, a line comprising talking conductors and a release conductor, a signal-control relay for the line controlled over the talking conductors, a signal normally controlled by said relay, and a key for causing the signal to be controlled over the release conductor.

In witness whereof, I hereunto subscribe my name this 23rd day of April, A. D., 1927.

THOMAS F. CROCKER.
